ARCHER W. RICHARDS, OF CLEVELAND, OHIO, ASSIGNOR TO THE HYDRAULIC PRESSED STEEL COMPANY, OF CLEVELAND, OHIO, A CORPORATION OF OHIO.

PROCESS OF UNITING METAL BODIES.

1,227,830.

Specification of Letters Patent. Patented May 29, 1917.

Application filed March 31, 1915. Serial No. 18,267.

To all whom it may concern:

Be it known that I, ARCHER W. RICHARDS, a citizen of the United States, residing at Cleveland, in the county of Cuyahoga and 5 State of Ohio, have invented a certain new and useful Improvement in Processes of Uniting Metal Bodies, of which the following is a full, clear, and exact description, reference being had to the accompanying 10 drawings.

This invention relates to processes for uniting metallic bodies by electric welding and more particularly to a process for uniting two metallic members or bodies (one of 15 which may surround the other.) The invention disclosed herein is shown as used for the purpose of uniting the head of a barrel to one of the ends thereof; and, while the invention is particularly well adapted to 20 the metallic barrel art, it will be understood that I do not propose to limit the use of my invention to this particular field, as it will be evident that it is capable of much more general application.

25 It is the general object of the invention to provide a process whereby metallic bodies or members may be united in a particularly efficient and economical manner. Further and more generally stated, the invention 30 may be defined as consisting of the combinations of steps set forth in the claims hereto annexed and exemplified in the drawings forming part hereof, wherein Figure 1 represents a central vertical sectional view taken through a portion of a barrel and showing the manner in which the head is inserted and welded in place therein; 35 Fig. 2 is a fragmentary sectional view illustrating a modification of the invention shown in Fig. 1; and Fig. 3 is a view, similar to Fig. 2, showing a still further modification.

Describing in detail and with the use of 40 reference characters the particular embodiments of my invention disclosed herein, 1 denotes the body of a barrel or other metallic article, the barrel being shown as provided with a cylindrical neck 2. Within the neck of the barrel there is shown a 45 head, said head comprising the closure plate 3 and a cylindrical flange 4. In Fig. 1, the head is shown as applied within the neck of the barrel with the plate 3 down and the flange projecting upwardly.

50 It is intended to electrically weld the

flange and neck together, after which the flange and neck will preferably be rolled inwardly to form a tube, indicated in dotted lines at 5, which tube will engage the plate 3 in a circular line located between the center and the periphery of the plate, substantially as pointed out and claimed in the application of J. H. Foster filed March 10, 1911 No. 613,589.

55 For the purpose of forming a satisfactory connection between the barrel neck and the head, the flange 4 will preferably be of such diameter as to form a snug or driving fit with the interior of the neck 2. Near its bottom, the neck will preferably 60 be provided with an inwardly extending bead or rib 6. The extent to which this bead or rib projects within the neck is necessarily exaggerated in the drawing for the purpose of illustration. In actual practice, 65 I have found that a projection of 2/100 to 3/100 inch for this bead or rib will produce satisfactory results.

70 The barrel head, having been inserted with a driving fit into the neck 2, encounters the rib or bead 6. In order to insert the head farther, it is forced in by means of a suitable press until the top of the flange 4 is flush, or substantially flush, with the top of the neck 2. This will bring the bead 75 or rib 6 preferably slightly above the plate 3. This insures a line contact between the flange 4 and the neck 2, and this line contact provides an ideal condition for electrically welding together the barrel head 80 and neck. In the drawings, the wheel electrodes of the electric-welding apparatus are indicated at 7 and 8 and are arranged to contact respectively with the outside of the neck 2 in the line of the rib or bead 6 and 85 with the inside of the flange 4 in line with said rib or bead. The rib or bead 6 is provided by rolling or pressing the metal, and this compacting operation secures a uniform gage of the metal through the rib or 90 bead and hence a line contact for the welding operation. Furthermore the rib or bead 6 provides a surface which can be quickly cleaned prior to welding. In brief, 95 this operation provides the three conditions necessary for resistance electrical welding, viz.:—contact, uniformity of gage of metal, and clean surface. After the parts have been united by electrically welding along 100 the line of contact, the flange and neck may 105

be rolled inwardly in the manner indicated and for the purpose explained hereinbefore.

In Fig. 2 there is shown a modification of my invention wherein the head flange 4 is provided with an outwardly projecting rib or bead 9 which is adapted to engage the inner surface of the neck 2. In other words, the rib or bead 9 is carried by the head flange instead of by the barrel neck. The amount of projection of this bead or rib will preferably be the same as that of the bead or rib 6 in Fig. 1, and the parts will be electrically welded in the same manner as is the case with the construction shown in Fig. 1.

In Fig. 3 there is shown a still further modification of the invention wherein the barrel head is inverted with the plate 3 substantially flush with the end of the neck 2 and the flange 4 projecting inwardly or downwardly. The flange 4 in this case is provided with the outwardly projecting rib or bead 10 similar to the rib or bead 9 but located closely adjacent to the plate 3. This arrangement has the advantage over that shown in Fig. 2 that the head has to be moved by a hydraulic press only the short distance required to move the rib from the top of the neck 2 to a point where the plate 3 will be substantially flush with the top of the neck.

The manner herein disclosed of uniting metallic articles has proven in actual operation to be extremely efficient, securing an absolutely tight and permanent joint between such parts and accomplishing this result in an extremely economical manner.

Having thus described my invention, what I claim is:—

1. The process of uniting an inner and an outer metallic member which consists in providing one of said members with a bead which is presented toward and adapted to engage the other member, the parts being of such diameter that the bead will engage its coöperating member under pressure thereby to secure a line contact therebetween, and electrically welding said members together along such line of contact.

2. The process of uniting a pair of metal members which are adapted normally to fit snugly the one within the other, said process consisting in providing one of said members with a bead presented toward the other member and adapted to engage the latter member under pressure, and electrically welding said members together along the line of contact between said bead and the adjacent engaging member.

3. The process of uniting a pair of metal members which are adapted normally to fit snugly the one within the other, which process consists in providing one of said members with a continuous bead presented to-

ward the other member and adapted to engage the latter member under pressure, and electrically welding said members together along the line of contact between said bead and the adjacent engaging member.

4. The process of uniting concentric metallic bodies which consists in providing one of said bodies with a continuous circumferential bead presented toward and adapted to engage the other body under pressure whereby a line contact is secured between said bead and such other body and electrically welding said bodies along such line of contact.

5. The process of uniting concentric inner and outer metallic bodies which consists in making the inner body of a diameter which will enable it to fit snugly within the outer body, providing one of said bodies with a circumferential bead presented toward the other body, forcing the bodies together whereby a line contact is secured between the bead and the coöperating body, and electrically welding said bodies along such line of contact.

6. The process of uniting cylindrical inner and outer metallic bodies which consists in making the inner body of a diameter which will enable it to fit snugly within the outer body, providing one of said bodies with a continuous circumferential bead presented toward the other body, forcing the bodies together whereby a line contact is secured between the bead and the coöperating body, and electrically welding said bodies along such line of contact.

7. The process of heading metallic barrels and like metallic objects which consists in providing such object with a neck having an inwardly presented circumferential bead, forcing into said neck a head having a flange adapted to engage the bead under pressure, whereby a line contact between said bead and said flange is secured, and electrically welding the head and neck along such line of contact.

8. The process of heading metallic barrels and like metallic objects which consists in providing such object with a substantially cylindrical neck having an inwardly presented circumferential bead, forcing into said neck a head having a cylindrical flange of substantially the same external diameter as the internal diameter of the neck, whereby a line contact between said bead and said flange is secured, and electrically welding the head and neck along such line of contact.

9. The process of heading metallic barrels and like metallic objects which consists in providing such object with a neck member and providing the head therefor with a flange member, providing one of said members with a circumferential bead presented toward the other member and adapted to

- engage such other member under pressure whereby a line contact will be secured between the bead and the member coöperating therewith, and electrically welding said members along such line of contact. 5
10. The process of heading metallic barrels and like metallic objects which consists in providing such object with a cylindrical neck member and providing the head there- 45
10 for with a cylindrical flange member of sub-stantially the same diameter as the internal diameter of the neck member, providing one of said members with a circumferential bead presented toward the other member, forcing 50
15 the head member into the neck member, whereby a line contact will be secured between the bead and the member coöperating therewith, and electrically welding said members along such line of contact. 55
20 11. The process of heading metallic barrels and like metallic objects which consists in providing such object with a neck member and providing the head therefor with a flange member, providing one of said mem- 60
25 bers with a circumferential bead presented toward the other member and adapted to engage such other member under pressure, whereby a line contact will be secured be- 65
30 tween the bead and the member coöperating therewith, said bead being so located that, when the parts are assembled prior to welding, the bead will be adjacent to the plate of the head, and finally electrically welding said members along such line of contact. 70
35 12. The process of heading metallic barrels and like metallic objects which consists in providing such object with a cylindrical neck member and providing the head there- 75
40 for with a cylindrical flange member of sub-stantially the same external diameter as the internal diameter of the neck member, pro-
viding one of said members with a circum-
ferential bead presented toward the other
- member, forcing the head member into the neck member, whereby a line contact will be secured between the bead and the member coöperating therewith, said bead being so located that, when the parts are assembled prior to welding, the bead will be adjacent to the plate of the head, and finally electrically welding said members along such line of contact. 45

13. The process of heading metallic barrels and like metallic objects which consists in providing such object with a neck and providing the head therefor with a flange, providing such neck with an inwardly extending circumferential bead adapted to engage the flange under pressure, whereby a line contact therewith is secured, said bead 60
being located adjacent to the plate or body of the head, when the head is positioned within the neck, and finally electrically welding the parts along such line of contact. 65
65
14. The process of heading metallic barrels and like metallic objects which consists in providing such object with a cylindrical neck and providing the head therefor with a cylindrical flange of substantially the same external diameter as the internal di- 70
ameter of the neck, providing such neck with an inwardly extending circumferential bead, forcing the head into the neck with the flange in close engagement with the bead whereby a line contact is secured, said bead 75
being located adjacent to the plate or body of the head when the head is positioned within the neck, and finally electrically welding the parts along such line of contact. 80

In testimony whereof, I hereunto affix my signature in the presence of two witnesses.
